US00D541701S

(12) **United States Design Patent** (10) **Patent No.:** **US D541,701 S**
Vasant (45) **Date of Patent:** **** May 1, 2007**

(54) **RECREATIONAL ELECTRIC CAR**

(76) Inventor: **Abraham Vasant**, 1587 Bluebell Ct.,
Livermore, CA (US) 94551

(**) Term: **14 Years**

(21) Appl. No.: **29/261,633**

(22) Filed: **Jun. 16, 2006**

Related U.S. Application Data

(63) Continuation of application No. 10/714,113, filed on Nov. 14, 2003, which is a continuation-in-part of application No. 29/183,300, filed on Jun. 9, 2003, now abandoned.

(57) **CLAIM**

The ornamental design for a recreational electric car, as shown and described.

DESCRIPTION

A portion of the disclosure of this patent document contains material to which a claim for copyright is made. The copyright owner has no objection to the facsimile reproduction by anyone of the patent documents or the patent disclosure as it appears in the Patent and Trademark Office patent file or records, but reserves all other copyright rights whatsoever.

FIG. 1 is a perspective view of a recreational electric car, showing a preferred embodiment of the new ornamental design.

FIG. 2 is a front elevation view thereof.

FIG. 2 is a leftside elevation view thereof; The right side view is a mirror image of the left side elevation of FIG. 3.

FIG. 4 is a rear elevation view thereof; and,

FIG. 5 is a top plan view thereof.

1 Claim, 5 Drawing Sheets
